3 Claims. (Cl. 315—3.5)

This invention relates to travelling wave electron discharge tubes and more specifically to such tubes of the kind in which an electron beam is projected axially down a delay winding which is coupled thereto. Such travelling wave tubes are now well known and in fairly common use for microwave amplification and other purposes.

As is well known, if a travelling wave tube of the kind referred to is to give high performance at microwave frequencies, it is necessary that the delay winding shall be precisely located in a mechanically stable manner with respect to the electron beam to which it is coupled, and various proposals have been made to satisfy this requirement which in practice is by no means easy to satisfy in an economical manner. For example, it is known to support the delay winding, which is usually a helix, by means of a plurality of (for example three) insulating support rods which extend parallel to the axis and contact with the periphery of the winding along lines equally spaced around said periphery, and to hold the rods with gentle but firm pressure against the winding by means of specially formed clamps encircling the plurality of rods at spaced points in their lengths. This type of construction has the defect that the clamps are troublesome to make and fit and even so are not always wholly satisfactory, since they provide clamping only at intervals along the lengths of the support rods. Another known expedient for fixing the delay winding in position in a stable manner consists of pre-glazing the support rods, assembling them with the winding in a jig, and applying heat treatment to cause the glaze to flow in such a manner as to stick the turns of the winding to the rods. This proposal is expensive to carry out and, moreover, may result in inacceptably increased radio frequency losses due to the glaze.

The object of the present invention is to provide simple and economical constructions for accurately locating the delay winding of a travelling wave tube of the kind referred to without incurring the defects of the known proposals above outlined.

According to this invention a travelling wave electron discharge tube of the kind having a delay winding which is co-axial with the electron beam path of the tube, is provided with a plurality of rods supporting said winding and in contact with the outside thereof along a plurality of lines distributed around the periphery thereof, and coiled strained metal spring means encircling said plurality of rods over at least a substantial proportion of the lengths thereof, said coiled metal spring means having, in the unstrained condition, a diameter less than that of a cylinder which would touch the peripheries of said rods, whereby spring force exerted by said coiled spring means presses said rods against said winding.

According to a feature of this invention a travelling wave electron discharge tube of the kind having a delay helix which is co-axial with the electron beam path of the tube is provided with a plurality of rods supporting said helix and in contact with the outside thereof along a plurality of lines distributed around the periphery thereof, and at least one helically coiled strained spring in a diametrically strained condition encircling said plurality of rods over at least a substantial part of the lengths thereof, whereby said metal spring, due to its strain, presses

2

said rods against said helix. There may be a single coiled spring extending over the required portion of the helix length or there may be a number of such springs, end to end or spaced apart a little, over said length.

5 Preferably there are three rods at 120° equally spaced round the periphery of the delay winding.

The invention is illustrated in the accompanying drawings which show, so far as is necessary to an understanding of the said invention, a travelling wave tube of the kind referred to and embodying the said invention. FIGURE 1 is a schematic elevation, broken away centrally and at the ends, of the embodiment in question, and FIGURE 2 is a sectional view at right angles to the view of FIGURE 1.

15 Referring to the drawings, the travelling wave tube therein partly represented has within a cylindrical envelope portion 1, shown broken away, a helical delay winding 2 between end members or so-called "chokes" 3. The winding 2 co-axially surrounds the electron discharge path (not represented) which extends axially along inside the said winding in the customary manner. The winding 2 is supported by three insulating rods 4, 5 and 6 spaced at 120° round the winding periphery and contacting it along three lines which are parallel to the axis. 20 So as to simplify FIGURE 1, the rod 6 is not shown therein, only the rods 4 and 5 being shown. The said rods are coated with graphite or other suitable resistance material over desired portions of their lengths to provide attenuation in accordance with well known travelling wave tube practice. Such graphite coating is indicated at 25 7 on the rod 4 only, it being not represented on the other rods, again for reasons of simplifying the drawing in FIGURE 1.

In accordance with this invention the rods 4, 5 and 6 30 are pressed inwardly on to the helix 2 by means of a coiled helical metal spring 8 long enough to extend at least over the greater part of the length of the helical winding 2 and having in its unstrained condition an internal diameter a little less than the diameter of the imaginary circle circumscribing the rods 4, 5 and 6 and to 35 which these rods are internally tangential. In FIGURE 1 the spring 8 is represented as wound in the opposite direction to that of the helix 2 but of course this is not necessary and, indeed, it is in general preferred to have the helix 2 and the spring 8 wound in the same direction. To fit the coil spring 8, the rods 4, 5 and 6 40 are placed in position and the spring 8 is unwound a little so as to increase its internal diameter sufficiently to allow it to be slipped over the said rods 4, 5 and 6.

45 50 It is then released when in the required position. It will be appreciated that, when released, the spring will provide radially inward forces which press the rods 4, 5 and 6 inwardly against the helix 2 and position the latter with precision and in a stable manner. It will further be observed that the inward pressure forces applied by the spring 8 are, to a close degree of approximation, uniform over the whole length of the spring so that a very 55 good and stable positioning and clamping action is obtained.

60 I claim:

1. A travelling wave electron discharge tube of the kind having a delay winding which is co-axial with the electron beam path of the tube, said tube including a plurality of rods which support said delay winding and 65 are in contact with the outside thereof along a plurality of lines extending parallel to the axis and equally spaced around the periphery thereof, and coiled strained metal spring means encircling said plurality of rods over the greater part of the length of said delay winding, said 70 coiled spring means having, in the unstrained condition, a diameter less than its diameter which it adopts when

encircling said rods, whereby spring force exerted by said coiled spring means presses said rods against said winding.

2. A travelling wave electron discharge tube of the kind having a delay helix which is co-axial with the electron beam path of the tube said tube including a plurality of rods supporting said helix and in contact with the outside thereof along a plurality of lines extending parallel to the axis and equally spaced around the periphery thereof, and at least one helically coiled strained metal spring in a diametrically strained condition encircling said plurality of rods over the greater part of the length of said delay helix, whereby said spring, due to its strain, presses said rods against said helix.

3. A tube as claimed in claim 1 wherein there are

three straight rods spaced at 120° round the periphery of the delay winding.
